UNITED STATES PATENT OFFICE.

ALBERT H. TAYLOR, OF EASTON, PENNSYLVANIA, ASSIGNOR TO INGERSOLL-RAND COMPANY OF JERSEY CITY, NEW JERSEY, A CORPORATION OF NEW JERSEY.

SPIKE-HOLDER FOR SPIKE-DRIVING MACHINES.

1.284.815.

Specification of Letters Patent. Patented Nov. 12, 1918.

Application filed January 30, 1917. Serial No. 145,428.

To all whom it may concern:

Be it known that I, ALBERT H. TAYLOR, a citizen of the United States, residing at Easton, in the county of Northampton and State 5 of Pennsylvania, have invented a certain new and useful Improvement in Spike-Holders for Spike-Driving Machines, of which the following is a specification.

the following is a specification:
This invention relates to pneumatic tools,
and especially to a tool of this type in which
the article to be acted upon is guided and re-
tained in place by a part of the tool.

The object of the invention is to provide a tool having a guide or holder for the article 15 acted upon which will properly guide and hold the article securely in place during a portion of the time it is being acted upon by the tool and will be automatically withdrawn from the article during the remainder 20 of the time.

20 of the time.
With this and other objects in view, the
invention consists in the features of con-
struction and operation set forth in the fol-
lowing specification and claims and illus-
25 trated in the accompanying drawings.

In the drawings forming a part of this specification:

Figure 1 is an elevation of a pneumatic tool provided with my guide or holder.

30 Fig. 2 is an elevation of the tool, partly in section,

Fig. 3 is a portion of the pneumatic tool provided with my attachment, with the parts in a different position,

35 Fig. 4 is a section taken on line A—B of Fig. 2, and

Fig. 5 is a detached view of one of the parts of this guide or holder.

In the modification selected for illustration, the invention is shown as applied to a tool adapted to drive spikes or other articles into wood or other material. In the drawings is shown a pneumatic tool having a front head 1, provided with an enlargement 2 in which are located slots 3 passing through the enlargement at an oblique angle. Sliding through the slots 3 are fingers 4, which, due to the angularity of the slots 3, are inclined to each other and at their lower ends 50 are adapted to come together and partly surround the spike or other articles to be driven. As shown in Fig. 4, the lower ends of the fingers 4 are preferably shaped to closely fit the spike or other articles to be driven, but this is not necessary, as the tool will act

satisfactorily if the spike is held by the fingers in any suitable manner. In order that the head of the spike may not become misplaced during operation, the striking piece 6 is fitted in the front head 1 of the pneumatic tool, so that portion of the front head 1 beyond the striking piece may provide a socket 5 sufficient to inclose the head of the spike. For convenience in placing a spike in the guide or holder a chain 8 is attached by one of its ends to the head of one of the fingers 4 and its other end is attached to a handle 7 or any other convenient part of the pneumatic tool. By means of this chain the workman can insert a spike in the holder or guide with but one hand by raising one of the fingers 4 with the chain while the tool is supported with the other. In order that the fingers 4 may not be in the way when the spike is driven nearly into position, the slots 3 are enlarged at their lower portions as shown at 9 in Fig. 2, so that as the lower ends of the fingers 4 take up against the material into which the spike is being driven they can enter these enlargements 9, thus allowing a spike to be driven entirely into place by this tool. This is clearly shown in Fig. 3. From the above it is thought that the operation of the guide or holder will be obvious.

obvious. It is to be understood that the present showing and description disclose only one specific modification of the present invention and other forms and modifications are included within the spirit and scope thereof, 90 as expressed in the appended claims.

What I claim is:

1. In combination, a pneumatic tool adapted to drive spikes or similar articles and a device for holding the spike or similar article when the driving starts, said device being arranged to be automatically thrown out of engagement with the spike when said device comes into contact with the material into which the spike is driven. 95 100

2. In combination, a pneumatic tool adapted to drive spikes or similar articles and a device for holding said spike or similar article when the driving starts, said device surrounding the spike or similar article and yieldingly engaging the material into which the spike or similar article is driven, said device being thrown out of engagement with said spike or similar article when said spike is partly driven. 105 110

3. In combination, a pneumatic tool adapted to drive spikes or similar articles and a device for holding said spikes or similar articles when the driving starts, said device surrounding the spike or similar article and directly engaging the material into which the spike or similar article is driven, said device being arranged to be automatically thrown out of engagement with said spike or similar article when said device comes into contact with the material into which the spike is driven.
4. In combination, a pneumatic tool adapted to drive spikes or similar articles and a device for holding the spike or similar article when the driving starts, said device comprising two obliquely extending fingers adapted to surround the spike or similar article, and being arranged to be automatically thrown out of engagement with the spike when said device comes into contact with the material into which the spike is driven.
5. In combination, a pneumatic tool adapted to drive spikes or similar articles and a device for holding the spike or similar articles when the driving starts, said device

comprising two obliquely extending fingers slidably mounted in said pneumatic tool, said fingers adapted to surround the spike or similar article, and being arranged to be automatically thrown out of engagement with the spike or other article when said device comes into contact with the material into which the spike is driven.

6. In combination, a pneumatic tool adapted to drive spikes or similar articles, and a device for holding the spike or similar article when the driving starts mounted upon the front head of said tool, said device comprising a plurality of obliquely extending fingers slidably engaging slots provided in said front head, said fingers adapted to surround the spike or similar article and being arranged to be automatically thrown out of engagement with the spike or similar article when the spike or similar article is partly driven.

In testimony whereof I have hereunto set my hand.

ALBERT H. TAYLOR.
